UNITED STATES PATENT OFFICE.

JOHN C. CROMWELL, OF CLEVELAND, OHIO, AND WILLIAM M. MEHLHORN, OF POTTSVILLE, PENNSYLVANIA.

OPEN-HEARTH FURNACE.

1,338,288.

Specification of Letters Patent. Patented Apr. 27, 1920.

Application filed June 26, 1917. Serial No. 176,959.

To all whom it may concern:

Be it known that we, JOHN C. CROMWELL and WILLIAM M. MEHLHORN, both citizens of the United States, residing, respectively, 5 at Cleveland, Cuyahoga county, Ohio, and at Pottsville, Schuylkill county, Pennsylvania, have invented a new and useful Improvement in Open-Hearth Furnaces, of which the following is a full, clear, and ex- 10 act description, reference being had to the accompanying drawings, forming part of this specification, in which—

Figure 1 is a view partly in plan and partly in horizontal section of a portion of 15 an open hearth furnace structure having a regenerator system embodying our invention;

Fig. 2 is a section on the irregular line II—II of Fig. 1; 20 Figs. 3 and 4 are vertical sections in planes at right angles to each other through one end portion of the furnace and one of the cinder pockets; and

Fig. 5 is a detail view of one of the locking devices for the removable bottoms of 25 the cinder pockets.

This invention has relation to open-hearth furnaces and more particularly to furnaces of this type in which powdered coal, oil, or 30 natural gas is used as a fuel. The invention is particularly useful in connection with furnaces in which powdered coal is used. The use of such fuel has been demonstrated to be a success, but existing furnaces are not 35 properly adapted to this use, owing largely to the lack of provision in such furnaces of proper means for cleaning the cinder pockets and regenerators, which quickly clog in the use of such fuel, the result being that 40 the efficiency of the furnace operations becomes seriously impaired.

Our invention is designed to provide an open hearth furnace with a regenerator system, which comprises a plurality of regenerator units of the vertical stove type, and which are so arranged that the different units may be readily cut out of action without disturbing the operation of the remaining units. These units are so constructed 45 and arranged that when cut out of operation, they can be readily and thoroughly cleaned or repaired.

A further object of our invention is to provide an improved construction and arrangement of the cinder pockets in the re-

generator connections, whereby such pockets may also be readily cleaned.

We attain these objects by the arrangement herein described, with the result that the efficiency of the regenerator system may 60 be at all times kept at or near the maximum.

Referring to the accompanying drawings, in which we have shown the preferred embodiment of our invention and which will now be described, the numeral 2 designates 65 the body portion of an open hearth furnace which may be, in general, of any suitable or usual type. Each end of the furnace is connected by an uptake 3, with a cinder pocket 4. In accordance with our invention, each of these pockets is constructed so that (as best shown in Figs. 3 and 4) there is an open space below the bottom of the pocket to permit of the putting into place and removal of a removable bottom 70 closure 5. This bottom closure is of pan form and may be handled in a manner similar to that employed for handling the bottoms of Bessemer converters, that is to say, it may be readily moved into and out 75 of place below the open end of the pocket 4 on a suitable jack car 6, running on tracks 7. When in place, it may be secured by any suitable means, such as the removable locking wedges 8, driven between lugs 9 on 80 the sides of the closure and suitable wedge blocks 10, carried on supporting columns 11 of the structure:

In further pursuance of our invention, we provide each side of the furnace with three 90 regenerator units 12, 13, and 14. These units are each of the vertical stove type generally similar to the hot-blast stoves employed in connection with blast furnaces and containing any suitable interior arrangement of checkerwork. Each unit 12 is connected to the adjacent end of the furnace by a flue 15, and each unit 13 is similarly connected to the furnace by a flue 16. The third unit 14 is connected to the units 100 12 and 13 by the respective flues 17 and 18. The units 12 and 13 have the outlet flues 19 and 20, respectively, which unite and are connected to a flue 21, leading to the stack; and the unit 14 has an outlet flue 22 also 105 connected to the stack connection or flue 21. Each of the flues 15, 16, 17, 18, 19, 20, 21 and 22 is provided with suitable controlling means, such as a valve or damper 23. Each of the flues 19, 20 and 22 is also provided 110

with an air inlet valve 24. Any suitable mechanical system may be employed for opening and closing these valves and for actuating the stove valves or dampers at 5 the proper times in reversing the furnaces, this operating mechanism forming no part of our invention.

It will be readily seen from an examination of Fig. 1 that in the normal operation 10 of the furnace, and assuming the outgoing gases to be passing from the end of the furnace nearest the top of said figure, that such gases will divide between the flues 15 and 16, passing (as shown in Fig. 2) to 15 the upper portions of the regenerator units 12 and 13, thence downwardly through said units, thence through the flues 17 and 18, to the lower portion of the unit 14, at one side. This unit has a central transverse vertical partition 14^a, which divides its interior into two reverse vertical passes. The gases entering the bottom of the unit at one side of the partition pass upwardly therethrough across the top of said partition, thence 20 downwardly at the opposite side thereof and to the outlet connection 21. At this time, the three air valves at the opposite end 25 of the furnace may be all opened, in which case, the incoming air will enter the bottom 30 of one compartment of the unit 14, pass upwardly through such compartment, downwardly through the other compartment, thence divide between the two flues 17 and 18, and then upwardly through the units 12 35 and 13, and through the flues 15 and 16 into the cinder pocket and uptake at that end of the furnace.

In case it is desired to cut the unit 12 at either end out of operation for the purpose 40 of cleaning or repairs, this can be readily done by closing the valves or dampers in the flues 15 and 17, respectively. If it is desired to cut out the unit 13, the valves or 45 dampers in the flues 16 and 23 will be similarly closed. If it is desired to cut out the unit 14, the valves or dampers in flues 17 and 18 will be closed. Under this condition, at the outgoing end of the furnace the gases will divide, flowing in parallel 50 through the two units 12 and 13, and thence through the outlet connections 19 and 20, the valves 23 in these connections, (which are closed when the unit 14 is in service) being now opened. At the incoming end of 55 the furnace, the air in like manner divides between the units 12 and 13. For the purpose of facilitating the cleaning of the several units, I provide a central pit, such as indicated at 25, and lateral pits 26. The 60 central pit is provided with extensions 25^a (shown in dotted lines in Fig. 1) and from which clean-out openings or passages 27 lead to the bottom of the respective units 14. Clean-out openings or passages 28 in like 65 manner lead from the base portion of one

of the units 12 and one of the units 13 into this pit. The remaining units 12 and 13 have a clean-out portion or passage 29, leading into one of the lateral pits 26.

The valves or dampers 21^a in the stack 70 flues or connections 21 are provided only in case it is desired to use a waste heat boiler in connection with the furnace. We have indicated such a boiler at 30 in Fig. 1. 31 designates the supply connections for the 75 boiler leading from the respective flues 21 back of the valves or dampers 21^a of such flues, and 32 is an outlet connection for the exhaust gases leading to the stack 33. 34 designates a fan or blower used in connection 80 with the circulation of the gases through the exhaust boiler.

The advantages of our invention will be appreciated by those familiar with this art, 85 since it provides an open hearth furnace having a regenerator system especially adapted to the use of powdered fuel (although also adapted to the use of oil or natural gas as a fuel) in which the regenerators may at all times be kept at or near 90 their maximum efficiency. The cleaning of the different units can be effected while the furnace is in operation and without any delays in such operation, the two units at each 95 end of the furnace, which are at all times in service, giving ample regenerative capacity while the third one is being cleaned or repaired.

Our invention also provides an extremely effective and convenient means for keeping 100 the slag pockets at all times free and clear of accumulation.

We do not desire to limit ourselves to the particular construction and arrangement of parts which we have herein shown and described, since it will be obvious that the construction and arrangement of the regenerator units, the several flues, the valves or dampers, etc., may be widely changed without departing from the spirit and scope of 105 our invention as defined in the appended claims.

We claim:

1. An open hearth furnace having three regenerator units for each end thereof, flue 115 connections, and controlling means for said connections, said connections and controlling means being constructed and arranged to permit either one or both of two of said units to be connected in series with the third 120 unit, or to be connected parallel with each other to the exclusion of the said unit, substantially as described.

2. An open hearth furnace having three regenerator units for each end thereof, flue 125 connections, and controlling means for said connections, said connections and controlling means being constructed and arranged to permit either one or both of two of said units to be connected in series with the third 130

unit, or to be connected parallel with each other to the exclusion of the said unit, said units being of the vertical stove type, substantially as described.

5. 3. An open hearth furnace having three regenerator units for each end portion thereof, separate flues connecting two of said units with the adjacent end of the furnace and with the stack, and other flues connecting each of said two units with the third unit, another flue connecting the third unit with the stack, and controlling means for said flues.

4. An open hearth furnace having three regenerator units for each end portion thereof, separate flues connecting two of said units with the adjacent end of the furnace and with the stack, and other flues connecting each of said two units with the third unit, another flue connecting the third unit with the stack, and controlling means for said flues, each stack flue connection having an air inlet.

5. An open hearth furnace having three regenerator units for each end portion thereof, separate flues connecting two of said units with the adjacent end of the furnace and with the stack, and other flues connecting each of said two units with the third unit, another flue connecting the third unit with the stack, and controlling means for said flues, each stack flue connection having an air inlet, there being a controlling device between each of the two first named units and the furnace and between them and the third unit.

6. An open hearth furnace having a plurality of regenerator units of the vertical stove type, means whereby one of said units may be disconnected from the furnace while the other units are in operation, and means giving access to the base of each unit for cleaning purposes.

7. An open hearth furnace having a plurality of regenerator units of the vertical stove type, and means whereby any one of said units may be disconnected from the furnace while the other units are in operation, there being a pit adjacent to each unit, and a cleaning passage or opening leading from the base of the unit to such pit.

8. In a regenerator system for open hearth furnaces, two regenerator units, each having a separate connection to the same end of the furnace and having an up-pass

therethrough, a stack connection for each of said units, a third unit connected to the lower portion of each of the two first named units, and the third unit also having a separate stack connection.

9. In a regenerator system for open hearth furnaces, two regenerator units, each having a separate connection to the same end of the furnace and having an up-pass therethrough, a stack connection for each of said units, a third unit connected to the lower portion of each of the two first named units, and the third unit also having a separate stack connection, said third unit having up-and-down passes therethrough.

10. An open hearth furnace, having a set of three regenerators for each end thereof, two of said regenerators of each set being connected in parallel with the adjacent end of the furnace, and the third regenerator of each set being connected to each of the other two of that set, each of said regenerators having a stack connection, and valve means controlling the several connections whereby any two of them may be operated to the exclusion of the other, substantially as described.

11. An open hearth furnace, having a set of three regenerators for each end thereof, two of said regenerators of each set being connected in parallel with the adjacent end of the furnace, and the third regenerator of each set being connected to each of the other two of that set, each of said regenerators having a stack connection, and valve means controlling the several connections whereby any two of them may be operated to the exclusion of the other, said regenerators being of the vertical stove type, substantially as described.

12. An open hearth furnace having a plurality of regenerator units for each end, cinder pockets intermediate the end of the furnace and the regenerators, a pit adjacent to each unit, and a cleaning passage or opening leading from the base of each unit to such pit, each cinder pocket having a bottom discharge opening and a detachable closure for said opening, substantially as described.

In testimony whereof, we have hereunto set our hands.

JOHN C. CROMWELL.
WM. M. MEHLHORN.
